UNITED STATES PATENT OFFICE.

ALBERT A. SOUTHWICK, OF PROVIDENCE, RHODE ISLAND.

DESIGN FOR A DISH.

SPECIFICATION forming part of **Design No. 26,397**, dated December 15, 1896.

Application filed November 6, 1896. Serial No. 611,300. Term of patent 7 years.

To all whom it may concern:

Be it known that I, ALBERT A. SOUTHWICK, a citizen of the United States, residing at Providence, in the county of Providence and State 5 of Rhode Island, have invented and produced a new and original Design for Dishes or Similar Articles, of which the following is a specification, reference being had to the accompanying drawing, forming part thereof.

10 The drawing is a top view of a dish or tray, showing my design.

15 The leading feature of my design consists in the raised ornamental border, in which foliated scrolls curve from a series of ornaments in opposite directions and are surmounted by a graduated beaded edge.

20 In the drawing, *a* indicates the panel; *b*, the raised and curved sides terminating in the flat band *c* on which the border is formed, consisting in the raised foliated stems *d d*, inclosing the panels *e e*, so as to extend radially from the curved portion *b* near the longer ends of the oval and form four distinct groups. The

foliated scrolls *ff* extend from the base of the stems *d d* and, curving in opposite directions, 25 meet at their outer curved ends in the center between the ornament formed of the foliated stems *d d* and the panels *e*. A graduated row of beads *gg* extend along the outer edges of the scrolls *ff* and abut at the center on the 30 larger beads *hh*. When the dish is required to be of circular form, the radial ornaments formed of the foliated stems *dd* and the panel *e* are disposed at equal distances.

Having thus described my newly-produced 35 design, I claim as new and desire to secure by Letters Patent—

The design for a dish or similar article herein shown and described.

In witness whereof I have hereunto set my 40 hand.

ALBERT A. SOUTHWICK.
